LAUNDRY WASHING MACHINE

Louis Zimark, Syracuse, N. Y., assignor to The Prosperity Company Inc., Syracuse, N. Y., a corporation of New York

Application August 6, 1935, Serial No. 34,936
Renewed August 31, 1938

9 Claims. (Cl. 68—58)

This invention relates to laundry washing machines having a clothes container, drum, or hydro-wheel, mounted in an outer casing, and has for its object a particularly simple drum construction by which a fluid, as a rinsing fluid, can be projected, when desired, into the drum from opposite ends thereof in the form of cylindrical curtains through which the clothes are tumbled.

10 It further has for its object the projecting of a fluid from opposite ends of the drum in machines in which the drum has a driving axle at one end, and an axial loading door at its other end.

15 It further has for its object a construction in which headers at opposite ends of the drum are connected by conduits extending lengthwise of the drum parallel to the axis and the fluid to be projected supplied to one of the headers.

20 It further has for its object the combining of the fluid projecting system in the drum construction so as to stiffen the drum structure in addition to providing the fluid system.

The invention consists in the novel features 25 and in the combinations and constructions hereinafter set forth and claimed.

In describing this invention, reference is had to the accompanying drawings, in which like characters designate corresponding parts in all the views.

30 Figure 1 is a perspective view, partly broken away, of a machine embodying this invention.

Figure 2 is an elevation, partly in section, of the clothes container, drum, or hydro-wheel, embodying this invention.

35 Figures 3 and 4 are sectional views on a reduced scale taken respectively on lines 3—3 and 4—4, Figure 2.

This invention comprises, generally, means for 40 projecting a fluid, as for instance, a rinsing fluid, into the drum or hydro-wheel from opposite ends thereof in a direction lengthwise of the axis of the drum from projecting points eccentric to the axis of the drum, thereby forming cylindrical curtains through which the clothes are tumbled 45 during the movement of the drum about its axis. Preferably, the projecting points at one end of the drum are located nearer the axis of the drum than the projecting points at the other end of the 50 drum, so that one curtain through which the clothes are tumbled is projected within the other cylindrical curtain. This results in the curtains not unduly obstructing each other, and in an even distribution of the fluid throughout the 55 length of the drum. The projecting or rinsing

system is particularly adapted for relatively long drums and also for drums in which the driving axle is at one end and the loading door at the other end of the drum.

1 It designates an outer casing and 2 the perforated drum or hydro-wheel mounted in the casing to rotate about a horizontally extending axis. During the washing operation, as is well known, the drum is oscillated about its axis or rotated a certain number of times in one direction and then reversed a certain number of times in the opposite direction, in order to slosh the clothes through a washing fluid within the lower portion of the outer casing up to a predetermined level. During the rinsing operation, the fluid is 15 drained out of the casing by opening a dump valve and the rinsing fluid projected into the drum, while it is being oscillated to tumble the clothes.

The casing 1 is mounted in a suitable base B 20 which may house mechanisms and parts accessory to or pertinent to the machine.

3 designates the axle at one end of the drum, and 4 the central or axial loading door at the opposite end of the drum, the axle 3 being journaled in a suitable bearing in the outer casing 1 and is connected in any suitable manner or through suitable motion transmitting means to a source of power or to an actuating mechanism.

The means for projecting the fluid into the 30 drum from opposite ends thereof, or, if desired, from the end in which the door opening is provided, comprises headers 5, 6, mounted on opposite ends or heads of the drum. One of these headers is connected to a fluid supply, and the 35 two headers are connected by conduits, so that the fluid is conducted from one header to the other. As here shown, the driving axle 3 is rigid and as here shown is integral with one header 5 and also is formed tubular or hollow and 40 communicates with the interior of the header 5. The passage of the axle 3 is connected to a fluid supply through a pipe 7 having therein a swivel joint, not shown. The pipe 7 extends around one side of the machine and has a control valve 7a 45 therein. The header 5 is discoidal in general form with its rim portion 8 bearing against the outer face of the adjacent head 9 of the drum and with a central portion 10 conoidal, carrying at the apex thereof, the axle 3. The header 6 is 50 annular in general form and located around the loading door opening 4 concentric therewith. The door opening 4 is usually provided with a suitable door frame structure 12 and the header 6 seats, as at 13, on the door frame 12. The door 55

opening 4 is aligned with a door opening, not shown, in the wall of the outer casing and is closed by a door D carried by the outer casing.

14 are conduits extending lengthwise of the drum 2 parallel to the axis of the drum and communicating at their ends with the headers respectively, these conduits thrusting at their ends at 15, 16, against the headers. The header 6 is formed with outwardly extending peripheral arms 10 6^a formed with nipples 6^b extending into the ends of the conduits and also extending at 6^c through openings in the head of the drum. The fluid enters the header 6 through the nipples and arms 6^a.

15 The drum or hydro-wheel is usually provided with inwardly extending hollow ribs 18, these ordinarily performing the function of tumbling the clothes during movement of the drum about its axis or of carrying the clothes during the rotation upwardly from the lower part of the drum to the upper part and letting them fall again to the lower part.

20 The conduits 14 are located within the hollow ribs, as shown. The peripheral walls or barrel 25 of the drum, as well as the ribs 18, are perforated in the usual manner.

25 Each end wall or head of the drum is provided with jet openings communicating with the headers 5, 6, respectively, the jet openings being arranged in annular series concentric with the axis of the drum and the radius of one of the series being different from that of the other series, so that the jets or cylindrical curtains formed by the jets do not unduly interfere with each other.

30 As here shown, the annular series of jet openings 20 leading from the header 5 are of less radius than the annular series of jet openings 21 leading from the header 6. The headers 5, 6 are secured together or are held assembled to the drum 40 by tie-bolts 22 extending through the headers and through the conduits 14. Owing to this construction, the tie-bolts clamp the headers against the heads of the drum and the ends of the conduits 14 and stiffen the entire drum structure, as well 45 as hold the headers and the conduits in assembled position.

35 In operation, while the drum is moving about its axis to tumble the clothes, the rinsing fluid passes from the supply pipe 1 into the hollow 50 axle 3, header 5, conduits 14, into the header 6, and is projected through the jet openings 20 leading from the header 5 and also through the jet openings 21 leading from the header 6, thereby forming two cylindrical curtains of different 55 diameters, so that one passes or telescopes within the other. This results in an even distribution of the rinsing fluid, particularly in relatively long drums.

60 What I claim is:

60 1. In a washing machine of the type having an outer casing and a perforated clothes container drum mounted in the casing to rotate about a horizontally extending axis, the combination of means for projecting fluid into the drum from opposite ends thereof in the form of cylindrical curtains, substantially concentric with the axis of the drum, the projecting points at the ends of the drum being arranged in an annular series and the annular series at one end being of greater radius than that at the other end.

65 2. In a washing machine of the type having an outer casing and a perforated clothes container drum located in the casing to rotate about a horizontally extending axis, the drum having an axle at one end and a central loading door at the other

70 end, the combination of means for projecting a fluid into the drum in a direction lengthwise of the axis of the drum provided with the loading door, said means comprising an annular header surrounding the loading door opening and provided with an annular series of jet openings directed into the drum.

75 3. In a washing machine, the combination of an outer casing and a perforated clothes container drum mounted in the casing to rotate about a horizontally extending axis, headers mounted on opposite ends of the drum and rotatable therewith and having jet openings spaced radially from the axis of the drum and directed into the drum, imperforate conduits extending lengthwise of, and rotatable with, the drum and connecting the headers, one of the headers being connected to a fluid supply.

80 4. In a washing machine, the combination of an outer casing and a perforated clothes container drum mounted in the casing to rotate about a horizontally extending axis, the drum having an axle at one end, and a loading door opening at its other end, headers mounted on opposite ends of the drum, one header surrounding the loading door opening, the headers having an annular series of jet openings directed into the drum, conduits extending lengthwise of the drum and connecting the headers, one of the headers being connected to a fluid supply.

85 5. A washing machine comprising an outer casing and a perforated clothes container drum mounted in the casing to rotate about a horizontally extending axis, the drum having hollow ribs extending inwardly from the peripheral wall thereof, headers mounted on the opposite end walls of the drum, each having an annular series of jet openings directed into the drum, one header being connected to a fluid supply, conduits located in the hollow ribs and extending between the headers, and tie-rods connecting the headers and extending through said conduits.

90 6. A washing machine comprising an outer casing and a perforated clothes container drum mounted in the casing to rotate about a horizontally extending axis, headers mounted on the outer sides of the end walls of the drum and having jet openings directed horizontally into the drum, conduits extending lengthwise of the drum and spaced radially from the axis thereof, and connecting the headers, one header communicating with a fluid supply, and tie-rods connecting the headers and extending through the conduits.

95 7. A washing machine comprising an outer casing and a perforated clothes container drum mounted in the casing to rotate about a horizontally extending axis, the drum having an axle at one end and an axial loading door opening at the other end, headers mounted on the outer sides of the end walls of the drum and having jet openings directed horizontally into the drum, one of the headers surrounding the loading door opening, conduits extending lengthwise of the drum and spaced radially from the axis thereof and connecting the headers, the header at the axle end of the drum communicating with a fluid supply, and tie-rods connecting the headers and extending through the conduits.

100 8. In a washing machine of the type having an outer casing and a perforated clothes container drum located in the casing to rotate about a horizontally extending axis, the drum having an axle at one end and a central loading door at the other end, the latter end being provided with an annular series of jet openings in the end wall

thereof around the door opening, and means for projecting fluid into the drum through said jet openings.

9. In a washing machine of the type having an outer casing and a perforated clothes container drum mounted in the casing to rotate about a horizontally extending axis, the combination of means for projecting fluid into the drum from opposite ends thereof in the form of cylindrical

curtains, the projecting points at the ends of the drum being arranged in annular series and the projecting points at one end of the drum being arranged out of alignment with those at the other end, whereby the cylindrical curtain 5 projected from one end of the drum does not encounter the curtain projected from the other end of the drum.

LOUIS ZIMARIK.
